WILLIAM WAY, SAMUEL B. WAY, AND SAMUEL C. POMEROY, OF SOUTH BUTLER, NEW YORK.

Letters Patent No. 63,677, dated April 9, 1867.

IMPROVED DISH WASHER.

The Schedule referred to in these Letters Patent and making part of the same.

TO ALL WHOM IT MAY CONCERN:

Be it known that we, WILLIAM WAY, SAMUEL B. WAY, and SAMUEL C. POMEROY, of South Butler, in the county of Wayne, and State of New York, have invented new and useful Improvement in Dish Washers; and we do hereby declare that the following is a full, clear, and exact description thereof, which will enable those skilled in the art to make and use the same, reference being had to the accompanying drawings, forming part of this specification, in which—

Figure 1 is a vertical longitudinal section taken in the line $z z$ in fig. 2.

Figure 2 is a vertical transverse section taken in the line $y y$ in fig. 1.

Similar letters of reference indicate corresponding parts.

This invention relates to certain new and useful improvements in dish-washing machine, whereby a very efficient and desirable machine is produced, as hereinafter explained.

In the accompanying drawings, A is a wooden box or frame, mounted on legs, and having a hinged cover, a . This box has a sheet-metal lining, B, which forms the washing vessel proper, as the wooden box in itself has no bottom. The metallic vessel B in general form has a round bottom, as seen in fig. 2, but this bottom has a depression, (C, fig. 2,) in its centre, running longitudinally the whole length of the vessel, and in cross-section, of a semicircular form. In this depression C lies the beating or washing-wheel D. The wheel D is composed of four long narrow wings, d , which have a concave or scoop form, as seen in fig. 2, and longitudinally, are disposed spirally around the centre or shaft of the wheel, as shown in fig. 1. The wheel D is held in place in such manner as to be removable for cleaning. One end of its shaft has a square coupling socket, e , (fig. 1,) which engages with a square-headed end section, f , of the shaft, and this section f has a neck or groove, g , which receives a pin, h , for holding it engaged with socket e , so that by withdrawing pin h the shaft f may be drawn back and disengaged from socket e , and the washing-wheel D is then free to be taken from the machine. Motion is given to the wheel D by band-wheels I and crank j . K is a wire rack for holding the dishes, and is removable, it being removed always before the wheel D can be taken out. The upper edges of the metallic lining B are turned inward horizontally, so as to form a projecting ledge or lip, b , and this ledge prevents water from being thrown out through the joint between the cover a and box A, when the machine is in operation. The edges of the cover a are bevelled so that if the cover is swelled by moisture it cannot jam in its seat, and will always open freely. For emptying the vessel a waste-opening, p , is made in its bottom, and is covered by a gate, M, swinging horizontally. This gate is fastened at one end by a pivot, n , (fig. 1,) and has a handle, m . The end of the gate opposite to pivot n is held up snug against the vessel by a rest, o , on which that end of the gate slides when moved for opening or closing. By the use of the concave-shaped wings or buckets, the tendency is for the wings to hold on to the water within their grasp until it has considerable rotative velocity, so that when the water does escape from the grasp of the wings it is thrown with greater force amongst the dishes. The spiral arrangement of the wings is intended to give the water, when thrown, a movement more or less toward one end of the machine, so that when plates are to be washed they are placed on edge in the rack with their dirty faces toward the opposite end of the machine, and a better result is thus obtained. By use of the depression C, the machine works equally well with a less quantity of water than would otherwise be necessary.

Having thus described our invention, what we claim as new, and desire to secure by Letters Patent, is—

The depression C, in the bottom of vessel B, for collecting all the water in the machine immediately about a wheel, D, which is in diameter considerably smaller than the diameter of the main chamber B, substantially in the manner and for the purpose set forth.

The washing-wheel D, having buckets with concave faces in a radial direction, and arranged spirally in a longitudinal direction, substantially as and for the purpose set forth.

The lateral sliding shaft f , and coupling e , in combination with a horizontal washing-wheel D and rack K, substantially in the manner and for the purpose herein specified.

The above specification of our invention signed by us this 21st day of March, 1867.

WM. WAY,
SAML. B. WAY,
SAMUEL C. POMEROY.
